2 Claims. (Cl. 19—106)

The present invention relates to a method of connecting fibrous ribbon issuing from a carding machine and broken due to stoppage of the fibre feeding and web delivery means and a guide apparatus according to the method. The method and apparatus according to the invention are particularly useful in connection with fully automatic carding machines.

In fully automatic carding machine the slivers issuing from the machines are not deposited in cans but are continuously deposited on a conveyor placed alongside of the machine or at a right angle thereto, the conveyor delivering the slivers to an apparatus placed at the end of a row of carders, for example a sliver winding apparatus or a drawing frame. Stoppage of the web delivery means and of the means feeding fibres to the carding machine while the carding cylinder continues to operate, as is usually the case, causes severing of the card web. In carding machines where the slivers are deposited in cans in the conventional manner, the broken card web is connected by hand whereby the new web is rolled in the broken end of the previous card web and is conducted through a funnel which is placed below the center of the doffer or doffing comb. This manual operation is not feasible in a fully automatic carding machine and must be replaced by a fully automatic operation.

It is an object of the invention to provide a method of connecting card web issuing from an automatic carding machine, which web has been broken due to a brief stoppage of the fibre feeding means and of the card web delivery means while the carding cylinder continued to operate. According to the invention a portion of the card web is caused to move on a longer path toward the funnel through which the web is withdrawn, than another portion whereby, after breakage of the web and upon restarting of the fibre feeding and web delivery means, the new web issuing from the doffer and doffing comb is allowed to overtake the portion of the first web moving on the longer path and is caused to fold into the first web. The speed at which the first web moves through the funnel is about equal to the speed at which the new web emerges from the carding machine.

It is a further object of the invention to provide a card web guide receiving the card web from the doffer and doffing comb of a carding machine and conducting the card web to a funnel or the like for forming a sliver and feeding the latter to the nip of a pair of calender rollers, said guide including asymmetric converging guide portions of different length for conducting the card web along said portions or paths of different lengths and causing folding of the card web as its moves toward the funnel.

With the method and guide means according to the invention dropping of the card web emerging from the doffer, upon starting of the fibre feeding and card web delivery means of the carding machine, is avoided and the card web is conducted toward the calender rollers which are placed at one side of the carding machine, whereby, due to the asymmetric construction of the guide means, the portion of the web emerging from the doffer at the side of the carding machine which side is distant from the calender rollers must travel along a relatively long path and therefore takes more time to reach the

2

funnel or trumpet than the card web portion emerging from the side of the doffer which is close to the calender rollers. This affords overtaking of the first portion of a card web which is already on the guide means after a breakage of the card web, by the new card web emerging from the carding machine and folding into and interlacing of the end of the first card web with the end of the new card web.

The novel features which are considered characteristic of the invention are set forth with particularity in the appended claims. The invention itself, however, and additional objects and advantages thereof will best be understood from the following description of an embodiment thereof when read in connection with the accompanying drawing, wherein:

FIG. 1 is a perspective schematic view of a carding machine provided with a card web guide apparatus according to the invention.

FIG. 2 is a schematic enlarged illustration of the card web delivery and guide means shown in FIG. 1, the figure showing a card web, which has been broken due to stoppage of the fibre feeding and web delivery means of the carding machine, and a new card web issuing from the carding machine after restarting the fibre feeding and web delivery means.

FIG. 3 corresponds to FIG. 2 and shows the apparatus a moment later when the new card web catches up with the end of the broken card web.

FIG. 4 shows the apparatus according to the invention after bonding of the new card web to the old card web.

Referring more particularly to FIG. 1 of the drawings, numeral 1 designates a fibre feed shaft feeding fibres to feed rollers 16 of a carding machine provided with a doffer 3 and a conventional doffing comb 4. A guide 5 for the fibrous ribbon or card web issuing from the doffer and doffing comb is provided adjacent to and below the doffer 3. This guide is formed by an asymmetric triangular declining guide plate which is mounted on a rod 6 connected to side shields 7 and 8 of the carding machine. Two converging and downwardly extending marginal portions 9 and 10 of the guide plate 5 are bent or rolled upward. One of said marginal portions, which is at the right side of the plate 5 in the drawings, declines to the left and extends almost over the entire width of the carding machine. This marginal portion 10 is preferably at least twice as long as the second (9) of said marginal portions, which extends in about parallel relation to the side shield 7. The lower ends of the converging marginal portions terminate adjacent to a funnel or trumpet 11 which is at one side of the carding machine. The latter causes the fibrous ribbon to form a sliver 13 and directs the sliver into the nip of a pair of calender rollers 12. The sliver 13 leaving the calender rollers 12 is received by an endless continuously moving flexible conveyor element 14 which is in the form of a longitudinally slit tube. For receiving the sliver the tube is spread open by a roller 15 which also diverts the sliver onto the element 14.

The delivery speeds of the calender roller pair 12, of the card feed rollers 16, of the doffer 3, and of the doffing comb 4 are coordinated to the speed of the conveyor element 14. No means for effecting this synchronization are shown, because they do not form part of the present invention.

The arrangement according to the invention operates as follows: Upon stoppage of the conveyor 14 the delivery of the doffer 3 and of the feed apparatus 16 must be stopped because there is no accumulating device between the conveyor 14 and the calender rollers 12. The fibre feed apparatus, the doffer 3 and the doffing comb 4 stand still whereas the carding cylinder 17 continues

to rotate so that the fibrous ribbon or card web is interrupted between the cylinder 17 and the doffer 3. If, after a short time, for example after less than twenty-five minutes, the feed apparatus 16, the doffer 3 and the conveyor 14 are restarted, the fibrous ribbon which has been interrupted between the cylinder 17 and the doffer 3 appears as shown in FIG. 2 after about one half revolution of the doffer. After restarting the calender roller pair 12 the fibrous ribbon 19 which rests on the guide plate 5 is drawn off at the delivery velocity v_a of the calender roller pair, which corresponds to the circumferential speed of the doffer and to the speed of the conveyor 14. The left side of the upper edge 20 of the ribbon 19 moves at the velocity v_a and requires the time t whereas more time $t' = l_r/v_a$ is required to move the right portion of the ribbon at the velocity v_a along the longer marginal portion 10 of the guide plate 5, the length of this marginal portion being l_r . This greater delivery time t' of the right portion of the ribbon 19 is sufficient for making a connection between the fibrous ribbon 21 moving from the doffer in a direction normal to the longitudinal axis of the doffer at the circumferential speed v_a of the doffer and the right side of the ribbon 19 moving away from the doffer at the velocity component v_n . The difference between the speed v_a of the ribbon 21 and the component v_n of the speed of movement of the ribbon 19 away from the doffer effects catching up of the right lateral marginal portion of the newly supplied ribbon 21 with the right side of the ribbon 19, which was on the guide plate 5 at the time the ribbon was severed. FIG. 3 shows the ribbons at the movement when the right portion of the new ribbon 21 catches up with the right portion of the old ribbon 19. Continued overtaking of the old ribbon by the new ribbon results in a loose connection of the ribbons progressively from the right sides of the ribbons to the left sides which connection is intensified by the folding of the ribbons effected by the marginal portions or rims 9 and 10, particularly by the right rim, of the guide plate 5 and a continuous sliver is once more formed in the condenser at the bottom of the plate 5 and fed to the rollers 12 as shown in FIG. 4.

If the doffer 3 stands still longer, for example, longer than about 25 minutes in a conventional carder, the flats 18, which continue to move, receive so much fibres from the cylinder 17 that, after restarting of feeding fibres to the carding machine, it takes a long time till the cylinder is refilled and the doffer 3 does not supply any or at first, only a useless fibrous ribbon. During this time the guide plate cannot produce the desired effect.

The optimal shape of the guide plate 5 is substantially a right angled triangle having a long cathetus parallel and adjacent to the doffing comb 4 and having a short cathetus extending from the left side of the doffer, as seen in the drawings, to the calender rollers 12, the triangle having a hypotenuse extending from the right side of the doffer 3 to the calender rollers. The corner of the triangle formed by the lower ends of the short cathetus and of the hypotenuse is cut off and the funnel 11 is placed thereat. The corner of the triangle formed by the upper end of hypotenuse and by the right end of the long cathetus is also cut off.

We claim:

1. In combination with a carding machine having a doffer, a doffing comb delivering a card web, and a trumpet receiving the delivered web;

a stationary card web guide means formed by a substantially plane metal sheet having substantially the configuration of a right-angled triangle whose acute angled corners are cut off, said metal sheet having a marginal portion representing the long cathetus of said right-angled triangle and being longitudinally adjacent to said doffing comb,

said metal sheet having a second marginal portion representing the short cathetus of said right-angled triangle, said second marginal portion being bent out of the plane of said metal sheet and extending between one end of said doffing comb and said trumpet for guiding one lateral marginal portion of the web on a relatively short path toward said trumpet,

said metal sheet having a third marginal portion representing the hypotenuse of said right-angled triangle, said last mentioned marginal portion being bent out of the plane of said metal sheet and extending between the opposite end of said doffing comb and said trumpet for guiding the opposite lateral marginal portion of the web on a relatively long path toward said trumpet.

2. In combination with a carding machine having a doffer, a doffing comb delivering a card web, and a trumpet receiving the delivered web;

a stationary card web guide means having substantially the configuration of an asymmetric triangle for guiding the card web from the doffing comb to the trumpet,

said guide means having a first marginal portion representing one side of said triangle and being substantially as long as and placed longitudinally adjacent said doffing comb,

said guide means having asymmetric marginal portions individually extending from the ends of said first marginal portion toward and converging at the trumpet and representing the second and third sides of said triangle,

one of said asymmetric marginal portions being at least twice as long as the second asymmetric marginal portion for guiding one lateral marginal portion of the card web on a relatively long path toward the trumpet and for guiding the opposite lateral marginal portion of the web on a relatively short path toward the trumpet,

the corner of the asymmetric triangle formed by said second and third sides and the corner formed by the long one of said asymmetric marginal portions and by said first marginal portion being cut off.
